UNITED STATES PATENT OFFICE

92,557

DESIGN FOR A MOLDING FOR PIECES OF FURNITURE

George J. Pike, Grand Rapids, Mich.

Application December 13, 1933, Serial No. 50,057

Term of patent 7 years

To all whom it may concern:

Be it known that I, GEORGE J. PIKE, a citizen of the United States, residing at 550 Paris Ave., S.E., Grand Rapids, in the county of Kent and State of Michigan, have invented a new, original, and ornamental Design for a Molding for Pieces of Furniture, of which the following is a specification, reference being had to the accompanying drawing, forming a part thereof, in which:

Figure 1 is a perspective view of the molding or of a panel, the distinguishing, essential and dominating feature or characteristic of the design being the motif per se which is shown in full lines, part of the horizontal, vertical and lateral dimen-

sions of the molding or panel being shown in dotted lines and indicating non-essential features of the design since the molding or panel may be used in the manufacture of numerous pieces of furniture, as for example with table tops, dresser rails, bed ends, mirror frames, chair backs and the like.

Figure 2 is an enlarged fragmentary view of the motif per se.

I claim:

The ornamental design for a molding for pieces of furniture as shown and described.

GEORGE J. PIKE.
